FOREIGN PATENT DOCUMENTS

AU 201414774 * 9/2014

Primary Examiner — Karen E. Eldridge Powers*Assistant Examiner* — Jasmine Mlinarcik(74) *Attorney, Agent, or Firm* — Caesar Rivise, PC(57) **CLAIM**

The ornamental design for a protective glove, as shown and described.

DESCRIPTION

FIG. 1 is a top isometric view of a protective glove showing my new design;

FIG. 2 is a top plan view of the protective glove of FIG. 1; FIG. 3 is a bottom plan view of the protective glove of FIG. 1; FIG. 4 is a right side elevation view of the protective glove of FIG. 1;

FIG. 5 is a left side elevation view of the protective glove of FIG. 1; and,

FIG. 6 is a top plan view of the protective glove of FIG. 1. The jagged, broken line at the base of the glove indicates the bounds of the claim and any portion of the article beyond what is shown forms no part of the claimed design.
